US0D1035887S

(12) **United States Design Patent** (10) Patent No.: **US D1,035,887 S**
(45) Date of Patent: ** Jul. 16, 2024

(54) **WEARABLE WALKING-ASSISTANCE
ROBOT FOR MEDICAL USE**

- (71) Applicants: **Hyundai Motor Company**, Seoul (KR); **Kia Corporation**, Seoul (KR)
- (72) Inventors: **Hyeon Jeong An**, Seongnam-si (KR); **Hyun Seop Lim**, Anyang-si (KR); **Seok Young Youn**, Seoul (KR); **Ju Young Yoon**, Suwon-si (KR); **Kyu Jung Kim**, Seoul (KR); **Ho Jun Kim**, Gunpo-si (KR); **Dong Jin Hyun**, Suwon-si (KR); **Sang In Park**, Suwon-si (KR)
- (73) Assignees: **Hyundai Motor Company**, Seoul (KR); **Kia Corporation**, Seoul (KR)

(**) Term: **15 Years**

(21) Appl. No.: **35/516,241**

(22) Filed: **Feb. 7, 2022**

(80) **Hague Agreement Data**

Int. Filing Date: **Feb. 7, 2022**

Int. Reg. No.: **DM/220499**

Int. Reg. Date: **Feb. 7, 2022**

Int. Reg. Pub. Date: **Feb. 10, 2023**

(30) **Foreign Application Priority Data**

Oct. 15, 2021 (KR) 30-2021-0048786

CLAIM

The ornamental design for a wearable walking-assistance robot for medical use, as shown and described.

DESCRIPTION

1. Wearable walking-assistance robot for medical use

1.1 : Perspective

1.2 : Perspective

1.3 : Front

1.4 : Back

1.5 : Left

1.6: Right

1.7: Top

1.8: Bottom

The broken lines depict portions of the wearable walking-assistance robot for medical use that form part of the claim.

1 Claim, 8 Drawing Sheets
